UNITED STATES PATENT OFFICE

RONALD M. WILSON, OF WAYNE, PENNSYLVANIA, ASSIGNOR, BY MESNE ASSIGNMENTS,
TO THE HUFFMAN MANUFACTURING COMPANY, A CORPORATION OF OHIO

PIPE CLOSURE

Application filed October 21, 1927. Serial No. 227,688.

My invention relates to pipe closures and more particularly to closures for the filling pipes of gasoline tanks which are usually installed below the level of the street and it is important that water and dirt be excluded from them.

In the ordinary screw type closure for this purpose, water accumulates around the cap and tends to enter the filling pipe when the cap is being replaced.

An object of my invention is to provide a closure with a double seal in which the inner gasket will engage its seat before the outer one does, whereby any excess accumulation 15 of water in the closure housing may flow out under the outer gasket.

Another object is to provide support for the inner gasket which will compensate for wear and to allow the cap to be firmly seated 20 on the outer gasket.

A further object is to provide simple and efficient locking means for preventing access to the tank by unauthorized persons.

A still further object of the invention is 25 to so arrange the parts of the device as to facilitate their construction and to provide for the renewal of said parts when they are worn or mutilated.

The above objects are attained by providing 30 a tubular housing having the bore thereof of varying diameter axially thereof affording shoulders on which a cap and other elements of the device may seat and by providing a sleeve removably attached to the housing. The sleeve provides a seat at its upper 35 end with which a suitable member on the cap may contact to seal the same, a second seal being provided for contact with one of the above mentioned seats and the relationship between the two seats being such that the sealing means cooperating with the sleeve will seat prior to the second sealing means thereby permitting the evacuation of any water about the sleeve before the second sealing 40 means is seated, compensation or the difference for the delayed seating of the outer sealing means, may be provided by means of a yielding member with which the inner sealing means is connected. A simple locking 45 means may be provided to cooperate with

the sleeve, the latter being provided with undercut shoulders to accommodate bolts extending from the lock. The sleeve referred to may be detachably secured in the bore of the housing so as to facilitate the construction of the bore as well as the construction of the sleeve particularly with respect to the undercut feature at its lower end.

In the description of the illustrative embodiment of my invention, reference may be had to the accompanying drawings, in which

Figure 1 is a cross sectional view, taken on the line 1—1 of Figure 2, and

Figure 2 is a top plan view of a preferred embodiment of my invention.

The closure housing 3 is preferably made of cast iron and has an opening 4 of varying diameters throughout its length with threads formed in the lower end of the opening for engaging the top of the filling pipe.

Slightly above the top of the threads 5, an annular shoulder 6 extends into opening 4, the upper edge of which forms a seat 7 for a cylindrical sleeve 8 which is preferably made of steel and held against removal by pins 9.

The lower end of the sleeve 8 is counterbored to provide a seat 10 for bolts 11 of a cylindrical lock 12, the diameter of which is but slightly less than the inner diameter of the sleeve 8. Where it is desired to use a lock 75 having a standard housing, a ring 13, which is slightly less in diameter than the inside of the sleeve 8, is fitted to the lock and secured thereto in any suitable manner.

The upper portion of the sleeve 8 is threaded externally to engage internal threads on a depending annular flange 14 of a cap 15 which is preferably made of cast iron; the diameter of the housing 3 being increased at this point to provide a recess between the inner wall of the housing and the outside of the sleeve 8. This recess is of sufficient size so that, when the cap 15 is screwed into place, a narrow channel 16 is left between the depending flange 14 and the housing 3.

The top of the cap 15 is of greater diameter than the flange 14, thus forming a horizontal flange which is undercut to form an annular groove in which a gasket 17 is placed. The diameter of the housing 3 is again increased 100

at this point to accommodate the top of the cap 15, thus forming an annular shoulder 18 against which the gasket 17 rests.

5 A recess 19 of any suitable configuration is formed in the cap 15 into which may be inserted a wrench for turning the cap. The one illustrated has side walls formed by arcs of equal radii, the arcs being struck from the points of intersection of the arcs. As this closure is ordinarily installed in a concrete walk or floor, I add grooves 20 so that the top of the closure will not become slippery from wear.

15 The underside of the cap 15 has a flat portion 21 with a boss 22 formed at its center and with its edges curved upwardly to merge into an annular groove 23 which extends into the inner wall of the flange 14.

20 A resilient disk 24, preferably of spring brass, is placed against the boss 22 and a gasket 25 placed against the disk, both being then suitably secured to the boss as by a screw 26.

25 The housing is screwed on the top of the filling pipe, the lock 12 inserted in the sleeve 8, where it will rest on the shoulder 6, and the key turned in the lock. Access cannot be then had to the tank as bolts 11 will engage the shoulders 12 on the sleeve. The disk 24 is preferably dished so that, when cap 15 is screwed down, gasket 25 will engage the top of sleeve 8 before gasket 17 is seated on shoulder 18. As the cap is screwed farther down, the resilient disk 24 holds the gasket 25 firmly 35 on the top of sleeve 8 and any excess water in the recess between the housing and sleeve 8 will be forced out through channel 16.

30 Where it is desired to make the disk 24 flat, the distance between the flat portion 21 and shoulder 18 is decreased. The disk then will bend upwardly until it meets the flat portion 21 and further screwing down of the cap will bend the disk and gasket into the groove 23. This groove is of such depth that a perfect 45 seal may be made when gasket 17 becomes thinner from wear, whether the disk 24 is dished or flat.

35 It is to be understood that the device as herein illustrated and described may be changed in various details without departing from the spirit of the invention as herein set forth and as hereafter claimed.

I claim:

1. A pipe closure including a housing having an opening therethrough, a cap adapted to be seated in the upper part of the housing but spaced therefrom, thereby forming a channel between the cap and housing when the cap is in closed position, a gasket adapted 50 to close the channel, and a second gasket carried by the cap adapted to close the opening in the housing, the gaskets being so disposed that the second gasket will seal the opening in the housing before the first gasket 55 seals the channel.

2. A pipe closure including a housing; a threaded sleeve secured within the housing, a cap having a depending flange threaded to engage the sleeve but spaced from the interior of the housing thereby forming a channel between the cap and the housing, a gasket seated upon the housing and adapted to be engaged by the cap to seal the channel, and a second gasket carried by the cap adapted to close the opening in the housing, the gaskets being so disposed that the second gasket will seal the opening in the housing before the first gasket closes the channel. 70

3. A pipe closure including a housing, a shoulder on the housing, a sleeve fixed in the housing, a cap having a horizontal flange, an annular gasket between the flange and shoulder, a depending flange formed on the cap and adapted to be threaded onto the sleeve, a disk adapted to seal the end of the sleeve, 85 a resilient disk abutting the sealing disk, a boss on the cap abutting the resilient disk, and means for securing both disks to the boss. 80

4. A pipe closure including a tubular housing having an internal shoulder, a sleeve having its lower end undercut to form a recess and resting on said shoulder, means securing the sleeve to the housing, a locking device seated within the sleeve and having bolts projectable into the recess in the sleeve, said sleeve being externally threaded at its upper end, a cap adapted for seating in the upper end of said housing and having a depending annular flange provided with threads adapted to engage with the threads of said sleeve. 90

5. A pipe closure comprising a housing having a sump, an insertable closure for said housing having a part penetrating the sump, 105 a yielding member carried by the closure and making closing contact with parts of said housing, a spring member carried by the closure acting upon and tending to hold said yielding member in intimate contact, and a gasket carried by the insertable member making closing contact later than said yielding member. 110

6. A pipe closure comprising a housing having a marginal rabbet within its upper 115 part, an insertable closure for said housing, a yielding member carried by the closure and making closing contact with parts of said housing, a spring member carried by the closure acting upon and tending to hold said yielding member in intimate contact, and a gasket within said rabbet forming closing contact, said gasket making closing contact later than the yielding member when the closure is inserted. 120

In testimony whereof I have signed by name to this specification.

RONALD M. WILSON.
